UNITED STATES PATENT OFFICE.

JOSEPH C. HUTTON, OF LOUISVILLE, KENTUCKY.

GAME APPARATUS.

Specification of Letters Patent. Patented Sept. 24, 1912.

1,039,133.

Application filed May 24, 1911. Serial No. 629,094.

To all whom it may concern:

Be it known that I, JOSEPH C. HUTTON, a citizen of the United States, residing at Louisville, in the county of Jefferson and 5 State of Kentucky, have invented new and useful Improvements in Game Apparatus, of which the following is a specification.

The invention relates to a game apparatus, and more especially to game boards.

10 The primary object of the invention is the provision of a game board of a nature in which a movable object may be shot thereon for scoring similarly to an ordinary game of base-ball, thus giving amusement to the players; and at the same time 15 requiring master skill on the part of any one player in the performance of the game to become winner.

Another object of the invention is the provision of a game board which enables a 20 game to be played that possesses and is imitative of all of the intricacies and amusement incident to an ordinary game of base-ball.

25 A further object of the invention is the provision of a device which permits the manufacturing thereof on an economical scale or at a minimum expense, and that will be strong, durable, and also reliable in 30 operation.

With these and other objects in view, the invention consists in the construction, combination and arrangement of parts, as will be hereinafter more fully described, illustrated in the accompanying drawings, and 35 pointed out in the claims hereunto appended.

In the drawings: Figure 1 is a top plan view of a game board constructed in accordance with the invention. Fig. 2 is a side 40 elevation thereof, the same being partly broken away. Fig. 3 is a sectional view on the line 3—3 of Fig. 1. Fig. 4 is a vertical longitudinal sectional view on the line 4—4 of Fig. 1. Fig. 5 is a detail view of the 45 movable object. Fig. 6 is a detail perspective view of the spring throwing device detached. Fig. 7 is a fragmentary perspective view of the board, showing the bumper or deflector block thereon.

50 Similar reference characters indicate corresponding parts throughout the several views of the drawings.

Referring to the drawings by numerals, 55 the game board comprises an elongated or substantially rectangular-shaped base board

10, with an upper flat face, and at the marginal edges of the said board are fixed vertical side and end walls 11 and 12, respectively, the same being of uniform height, and are connected together at their adjacent ends in any suitable manner, the walls being designed to form guard rails for preventing the rolling off from the board of a 60 movable object, presently described.

Printed or otherwise marked upon the upper face of the base board 10, near one end thereof, is a diamond-shaped frame 13, which is designed as a representation of a base-ball diamond or infield, and within which are indicated by suitable indicia, the 70 home-plate 14, the first, second, and third bases 15, 16 and 17, and the pitcher's box or stand 18, respectively.

Outside of the infield or diamond, and extending therefrom to the opposite end of 75 the board, is laid out or defined an outfield, in which are arranged at suitable intervals pockets 19, the same being formed in the base board 10, the movable object engaging 80 therein when thrown in a manner presently described. Suitable indicia are printed adjacent the pockets 19 for indicating various plays which may be made during a game, such as a base hit, an out, a fly ball and so 85 forth.

At the pitcher's stand 18 and cut into the board is an elongated transversely disposed slot 20, through which projects, above the upper face of the board 10, a vertical spring arm 21, the upper end of which is formed 90 with a striking loop 22, and its opposite lower end is outturned, as at 23, to lie against the outer face of the said board 10. This outturned end 23 has passed through the same a suitable fastening member 24 95 which is engaged in the board, thereby securing the spring arm thereon, the arm being designed to strike the movable object, comprising a resilient spherical-shaped body 25, so as to shoot the same across the home-plate 14, whereby it will strike a bumper or deflector device, hereinafter described.

The bumper or deflector device comprises a bowed plate or block 26, the bow thereof being directed toward the pitcher's stand 18, 105 so that when the ball strikes the same, it will be rebounded in the direction of the infield and outfield represented upon the board, and in the course of travel of the said ball, the latter will roll into any one of the pock- 110

ets 19, thereby making the play which is to be indicated adjacent the pocket in which said ball rolls.

Outside of the infield and outfield and formed in the upper face of the board 10 are columns of spaced sockets 27, in which are engageable counting pegs 28. At the head of one column is printed or otherwise indicated the word "Out," while the other column is headed by the word "Runs," so that upon engaging the pegs in the sockets in the columns, respectively, a complete score may be kept for each player.

In the playing of the game, the respective players are formed into independent teams, one being designated the "battery" team, and the other the "field" team, and when the players of the battery team are out, the field team takes their places, so that the scores of each team are kept, and the rules and manner of playing the game is imitative, as nearly as possible, of those of an ordinary game of base-ball. The small diamond in the lower left hand corner of Fig. 1 is for the purpose of indicating when players are on the different bases, by the insertion of counting pegs in the sockets 27.

What is claimed is:

1. In a game apparatus, in combination, a playing board marked off to indicate a baseball diamond, a pitcher's stand located within the diamond and indicated on the said board, the said board being provided with a slot contiguous to the said pitcher's stand, a resilient arm passed vertically through the

slot to protrude beyond the upper face of the board and having a striking head at its upper end, and an outturned lower end, means securing the outturned end of the arm to the under face of the board, and a deflector plate rising from the upper face of the board in spaced relation to and in alignment with the resilient arm to be struck by a missile shot by said arm.

2. In a game apparatus, in combination, a playing board marked off to indicate a baseball infield and outfield, a pitcher's stand located within the diamond and indicated on the said board, the said board being provided with a slot contiguous to the said pitcher's stand, a resilient arm passed vertically through the slot to protrude beyond the upper face of the board and having a striking head at its upper end, and an outturned lower end, means securing the outturned end of the arm to the under face of the board, a deflector plate rising from the upper face of the board in spaced relation to and in alignment with the resilient arm to be struck by a missile shot by said arm, the said board being provided with a plurality of pockets, said pockets being adapted to receive said missile after the same has struck the deflector plate.

In testimony whereof I affix my signature in presence of two witnesses.

JOSEPH C. HUTTON.
